SLICING MACHINE

**David A. Meeker, Troy, and Ernest A. Reussen-
zehn, Dayton, Ohio, assignors to The Hobart
Manufacturing Company, Troy, Ohio, a corpo-
ration of Ohio**

Application December 20, 1946, Serial No. 717,566

4 Claims. (Cl. 146—102)

1

This invention relates to slicing machines.

It is the principal object of the invention to provide a slicing machine of the gravity feed type which is simple and economical in construction and which is so arranged that with a minimum of effort the entire machine can be maintained in a clean and sanitary condition.

It is also an object to provide such a machine which is constructed with a minimum number of parts which can be easily and cheaply manufactured and assembled, and in which the parts exposed to the foodstuff may be given a smooth surface finish facilitating the maintenance of the entire machine in a clean and sanitary condition.

It is a further object to provide a frame which extends in impervious relation beneath the knife and the path of travel of the carriage and which is shaped in such manner as to facilitate the cleaning of the machine and the discharge of scraps of the work material rearwardly and onto a slice tray removably provided at one end of the machine and in position to receive the slices directly thereon.

It is another object to provide such a slicing machine which incorporates a simple and effective mechanism for mounting and adjusting the gage plate assuring accuracy of setting and substantial freedom from looseness and play.

It is also an object to provide such a gravity feed machine having a downwardly inclined work receiving carriage firmly mounted for reciprocation on a supporting frame such that the machine operates smoothly and freely and substantially without play under all normal forces which are applied during use.

It is a further object to provide a pusher plate construction which is normally biased to a pre-determined position which assures the proper engagement with the work material when the same is used for feeding the work to the knife, and in which it is properly oriented so that when swung out of the carriage to its inoperative position, it will be held in proper position to be received in latching engagement over an abutment where it is held by gravity.

It is a still further object to provide a simple and satisfactory construction of knife guard plate which does not interfere with the normal feeding of the work material during use and which may readily be removed for cleaning and the like.

Other objects and advantages will be apparent from the following description, the accompanying drawings, and the appended claims.

2

In the drawings:

Fig. 1 is a view in perspective of a slicing machine constructed in accordance with the present invention;

5 Fig. 2 is an end elevational view of the same from the operator's end of the machine;

Fig. 3 is a plan view of the machine;

10 Fig. 4 is a side elevational view of the machine with the pusher plate in its inoperative position;

15 Fig. 5 is a partial vertical sectional view showing the knife and its supporting and driving mechanism on the line 5—5 of Fig. 3;

Fig. 6 is a partial vertical sectional view centrally through the work supporting carriage and the frame on the line 6—6 of Fig. 3;

20 Fig. 7 is a detail view partially in elevation and partially in section showing the mechanism for adjusting the position of the gage plate on the line 7—7 of Fig. 2;

Fig. 8 is a view partially in plan and partially in section showing the construction of the pusher plate;

25 Fig. 9 is a perspective view of the end of the pusher plate arm showing the construction which protects the machine from accidental contact with the pusher plate;

Fig. 10 is a sectional view showing a detail of the mechanism for securing the knife plate in place;

30 Fig. 11 is a view similar to Fig. 6 but showing a detail of the slide construction for mounting the carriage showing the means for securing lubrication of the carriage supporting bearings, on the line 11—11 of Fig. 12;

35 Fig. 12 is a detail sectional view on the line 12—12 of Fig. 11;

Figs. 13 and 14 are views showing different positions of the pusher plate with respect to the work carriage;

40 Fig. 15 is a bottom view of the forward portion of the machine looking upwardly from beneath the same;

Fig. 16 is a vertical sectional view through the frame of the machine rearwardly and below the knife, and on the line 16—16 of Fig. 2;

45 Fig. 17 is a detail sectional view through the rail on an enlarged scale showing the retainer clip for detachably securing one end of each of the slide rails in position;

Fig. 18 shows a similarly enlarged side view of the rail with the clip mounted into place;

Fig. 19 is an enlarged details view of the mounting for the opposite end of the rail; and

55 Fig. 20 is a small subassembly of the knife and

knife guards to show the location of the notches that receive the lugs on the knife plate.

Referring to the drawings which disclose a preferred embodiment of the invention, the machine comprises a main base member 10 which extends across the entire lower portion of the machine, serving as a base and main supporting frame. The under surface of the main frame member is suitably ribbed as shown at 12 (Fig. 15) to afford additional strength while avoiding unnecessary weight. Preferably this member is made of a relatively light weight material such as a suitable aluminum-containing alloy so as to reduce the overall weight and keep the machine readily portable. If desired the outer exposed surface may be suitably finished to provide a smooth surface which can be readily kept in a clean and sanitary condition, such surface being either painted or preferably anodically treated. The base carries mountings for rubber cushion members 14 which may be located at the four corners to provide for resiliently supporting the entire machine in non-slipping engagement and with the lower edge of the main frame raised slightly above the supporting surface.

At one side the frame member 10 is formed with a generally rectangular opening 16 (Fig. 16) having a surrounding rim which is relatively flat on top and thus is adapted to receive a slice tray 17. Preferably the frame member is grooved as indicated at 18 (Fig. 16) and 18' (Fig. 2), the grooves extending at right angles to each other alone one side and end providing for the edge of the tray being slidably received and locked in position in the groove so formed. The tray is retained in the groove by a single screw 19 which is accessible from the lower side of the frame and which is located in the outer corner as shown in Figs. 3 and 5. Tray 17 may suitably be formed as either a molded metal, stamping or plastic element, the surface of which is smooth and easy to maintain in a clean and sanitary condition and as will be evident from Figs. 2, 3 and 6, extends over a substantial part of the length and width of the base, entirely underlying the gage plate and the cutting portion of the knife.

The base is formed with an integral upwardly extending part 20 at the rear side thereof, and within this portion there is received the drive motor, the end cap of which is shown at 21 (Fig. 1). The motor thus stands with its drive shaft substantially horizontal. On the forward side, the main frame is provided with an integral upwardly extending curved part 22 which extends along the front face of the machine with a vertically extending wall portion 23 (Fig. 6) on the forward side, such curved portion 22 forming an enclosed cover construction for enclosing and protecting the slide rods on which the carriage is mounted.

Between the rearward portion 20 and the forward portion 22, the frame is formed with an integral curved part or collecting trough 25 which has a definite slope from the rear of the machine downwardly toward the slice tray 17, as shown in Fig. 16. As shown in Fig. 5 the trough 25 extends forwardly beyond the lower edge of the knife and fully underlies the entire cutting arc of the knife and the adjacent portion of the gage plate where scraps are most likely to fall. Such scraps are received in the trough and either discharged downwardly onto the slice tray, or are collected in a location from which they may be easily removed by the operator who has ready access to this portion of the machine because of

the substantial radius of curvature of the portion 25 and the freedom of access from both ends thereof. The frame thus affords a continuous closed construction extending in impervious sealed relationship throughout the entire base of the machine, preventing downward passage of scraps of food material to the space below the frame, and facilitating the collection and discharge of all such material in a location from which it can be easily removed by a simple wiping operation.

The motor shaft is shown at 30 (Fig. 5) extending into the raised portion 20 of the frame and having secured thereon drive worm 31 which meshes with a worm gear 32 keyed by means of key 33 to a knife shaft 34. A lock nut 35 kept tight by screw 36 provides for detachably securing the worm gear 32 in position on the shaft.

The knife shaft is journaled in ball bearings 37 and 37' respectively which are supported in a sleeve member 38 supported in the rear frame element 20. Bolts 39 provide for removably securing the sleeve in position. As shown in Fig. 5, the shaft is supported at an angle to the horizontal of about 45°, such that it will provide for the proper driving and support of the rotary knife in the desired plane. The motor is suitably controlled by means of a snap switch 40 (Fig. 2) mounted at a convenient location in the base, preferably adjacent the operator's position.

The knife 45 (Fig. 5) is formed with a recessed face 46 and is suitably secured to the knife shaft 34 by means of a series of bolts 47, the knife being centered on the projecting end 48 of the knife shaft. Suitable sealing elements 49 prevent escape of lubricant outwardly onto the knife surface. A center abutment pin 49a of fiber or the like is adjustably threaded into the end of the knife shaft to form a support for the knife guard plate and seats against an inner threaded pin 49b of steel. The inner pin is first positioned in proper location and then the outer pin seated against it, the rotation of the knife keeping the outer pin tight against the inner pin.

Sleeve 38 is provided with a flanged portion 50 and with a peripherally grooved portion 51 which is adapted to receive the locking flange 52 of a pair of knife guard members comprising lower member 53 and upper member 54. The two knife guard members 53 and 54 each cover approximately half of the knife periphery, and are adapted to be inserted and removed in a predetermined order of sequence. Thus the flange 52 of the knife guard member 53 is provided with an inwardly extending lug 56 (Fig. 20) which passes through a slot 57 in flange 50, and upon the subsequent turning of the knife guard member 53 about the axis of the shaft 34, locking lug 56 will engage and lock into the groove 51' (Fig. 5) to prevent direct withdrawal of the guard member while allowing it to rotate around to its final operative position where it engages a stop pin. After the lower guard member 53 has been so positioned and locked in place the upper guard member 54 is moved downwardly into position without rotation, this member carrying a lug 60 having a tapered opening 61 therein which is adapted to align with a pin 62, carried as shown in Fig. 5 in frame member 20. Pin 62 is yieldably urged toward locking position by means of spring 63, but may be manually withdrawn through the operation of a button 64 attached to the end of the pin and accessible on the outside of the frame. When the upper guard member 54 is to be positioned in operative position it may be pressed downwardly

and pin 62 will snap into position to retain both guard members in locked position. The end of the pin 62 is tapered and thus a firm locking engagement is established when the tapered pin engages the correspondingly tapered opening 61. Preferably the lower end 66 of the lug 60 is likewise tapered so that as the guard is move downwardly into operative position the tapered end 66 contacts the tapered pin 62 to cam the pin backardly and thus facilitate the establishment of the proper locking relation. In order to remove the guard it is necessary for the operator manually to move button 64, withdrawing pin 62 from engagement in slot 61. No manual operation however is required to lock the guard in place and the guard can thus be assembled by a simple movement of one hand. Cross reference is made to copending application Serial No. 455,808, now Patent No. 2,412,962 filed August 22, 1942, and assigned to the same assignee as this application which shows certain of the features described above.

In order to protect the front face of the knife and to provide support for the work material after the same is reciprocated across the knife face, a knife guard member or knife plate 70 is provided which as shown in Fig. 3 overlies the greater part of the front face of the knife, leaving only the cutting edge 71 thereof exposed. Preferably the knife guard is likewise recessed as shown at 72 (Fig. 5) to fit within the recessed face of the knife and provide a smooth supporting surface for the work material as it moves across the face of the knife. The knife plate 70 is supported from the knife guard 53, 54 through the provision of a plurality of spaced arcuate recesses 73 and 74 (Figs. 10 and 20) in the lower knife guard 53 within the annular rib 75 on the front face thereof. Similar recesses 76, 77 are formed in the same relative positions upon guard 54. Co-operating with such recesses are lugs 78, which are formed integrally with plate 70 and shaped to correspond with the recesses to thus lock the knife plate in properly supported operative position. A handle 79 secured to the upper portion of the knife plate provides for convenient handling thereof.

In the assembly and removal of the knife plate 70, the lower guard member 53 is first placed in operative position as described above and knife plate 70 is then moved into operative position with its two lower lugs 78 engaging in the lower grooves 73 and 74. The upper knife guard member 54 is then moved downwardly into operative position in the manner described above, this movement providing for the upper pair of lugs 78 being received in the upper groove 76, 77 where it is locked in place to thus securely support the knife guard in operative position against the downward force applied by the work material moving in the carriage. The abutment 49a is suitably adjusted to support the plate from the center thereof to avoid deflection under load. It will also be clear that with this construction the knife guard is prevented from movement either in the plane of the knife, normal thereto, or with a rotary motion, and is thus securely held in proper operative position while at the same time it may be readily removed for cleaning and as easily reassembled. As will be clear from Fig. 5, the lower guard 53 because of its angular mounting upon the inclined knife does not obstruct the scrap passage 25 but leaves it free and clear for application of a cleaning cloth in the hand of the operator.

A gage plate is shown at 80 (Figs. 2, 3 and 6), and it is mounted in side-by-side relation with the knife and at such an angle that it is substantially parallel with the plane of the knife, both of these elements being supported with their plane substantially normal to the downwardly inclined path of travel of the work material moving through the carriage. Means are preferably provided for adjustably supporting the gage plate to provide for the movement thereof in planes which remain parallel with the knife plane, while at the same time providing for increasing the lateral spacing between gage plate and the knife as the thickness of the slice is increased, the gage plate being at all times firmly supported so that it is substantially free of looseness or play as it periodically supports or engages the work material as the same is reciprocated in the carriage.

This construction comprises a gage plate support 81 at the rear of the gage plate on which the gage plate is mounted by means of a series of bolts 82 through the use of a clamping plate 83. The member 81 projects downwardly in enclosing relation over the clamping plate structure to facilitate the maintenance thereof in a clean and sanitary condition. The support 81 carries a pair of guide pins 85 and 86 which are slidably mounted in openings in projecting bosses 87 which are formed in the wall of the main frame element 22 (Fig. 6). As shown the bosses 87 have substantial axial extent, and project entirely through the cover member 22 to provide an extended area of support. The pins 85 and 86 are thus guided for sliding movement so that the gage plate or at 35 moves parallel with the plane of the knife or at an angle to the horizontal of approximately 45°. In addition as shown in Fig. 15 the two pins do not extend directly transverse of the machine, but are mounted at an angle of approximately 30° thereto, this being the construction which provides for increasing the gap between the edge of the gage plate and the knife, as the thickness of the slice is increased.

The mechanism for adjustably setting the gage plate comprises a hand wheel 90 rotatably carried on a shaft 91 (Fig. 7) journaled in a boss 92 formed integrally in the end portion 93 of the main frame member 10, the hand wheel carrying suitable indicia on its skirt indicating the slice thickness. In order to take up any end play in shaft 91, a pair of lock nuts 94 are threadedly received over the forwardly projecting end of the shaft and are suitably tightened against the frame member 93 to prevent such end play.

In order to provide for zero adjustment of the gage plate, the forwardly projecting end of shaft 91 is threaded both externally and internally. Lock nuts 96 mounted on the external threads receive between them a drive plate 97 which has a pair of apertures 98 through which the locking and driving pins 99 and 100 are received. Preferably the two pins 99 and 100, as well as the respective apertures in which they are received in plate 97, are located at different radial distances from the center and hence can be received in only one relative assembled position. The hand wheel is removably secured on the end of the shaft by means of a screw 101 engaging in the internal shaft threads. A stop pin 102 is fixed in the boss 92, clearing the shorter pin 100 and projecting into the path of the longer pin 99, thus forming a stop to prevent more than a single revolution of the hand wheel. Furthermore it provides for relieving the lock nuts 96 of excessive strain in the event that the operator at-

tempts to force the rotation of the hand wheel beyond the limiting position in either direction.

From the above it will be clear that the screw 101 having been removed, the hand wheel 90 may be directly withdrawn thereby exposing the adjusting mechanism. By loosening and resetting the lock nuts 96, the zero position of the drive plate 97 can be adjusted. When the parts are then reassembled in the manner shown in Fig. 7, the new adjustment is definitely secured and no further manipulation of the setting mechanism is necessary, the hand wheel being merely moved into position and secured by screw 101, entirely enclosing and protecting all the adjusting mechanism.

A coarse threaded spiral worm 105 is secured to the end of shaft 91, the threads preferably having tapered side walls. A follower pin or shoe 107 (Fig. 6) having a matching tapered end is carried by a lever member 108 being axially movable therein and yieldably urged into engaging relation by means of a leaf spring 109 bolted to the lever. The lever is pivotally mounted at an angle of about 45° to the horizontal by means of bolt 110 to a boss 111 which projects downwardly from the portion 22 of the main frame member as shown in Fig. 6. A slot 113 is formed in the end of lever 108 and a pin 114 which is secured to guide pin 86 travels in this slot 113 to cause axial travel of the pin as the shaft is turned.

From this description it will be evident that upon the rotation of hand wheel 90, shaft 91 and worm 105 are rotated, follower 107 traveling in the worm groove and causing the swinging of lever 108 about the axis of bolt 110. This produces an arcuate travel of slot 113, causing the pin 114 to effect an axial movement of guide rod 86, thus moving the gage plate 80 in the plane of movement as previously described. It will be further noted that the follower 107 is yieldably urged into continuing engaging relation in the worm groove 105, and is thus adapted to maintain a close working fit eliminating looseness of play or backlash even after extended periods of use and notwithstanding the continuing variations in loading applied thereto under the feeding action of gravity, supplemented to a greater or lesser extent by manual pressure. It is thus only necessary properly to determine the zero adjustment of the gage plate, and the remaining settings will be accurately reproduced, without lost motion or backlash. Preferably the engaging surfaces of the follower 107 and the spiral groove in the worm are surface hardened to minimize wear.

In order to support the carriage for its reciprocating movement with its work receiving surface inclined downwardly at the proper angle, a pair of parallel guide rods 120 and 121 (Figs. 6 and 15) are fixed in position in the main frame of the machine. As shown in Fig. 6 rod 120 is located below and laterally displaced with respect to rod 121, both such rods being within the portion of the frame enclosed by member 22. In order to provide for assembly and removal of the rods while maintaining the maximum available axial length thereof, each rod adjacent its one end is provided with a grooved portion 123 (Figs. 15 and 18) within which there is received a retainer clip 124 which has a right angularly bent flange 125 to facilitate handling (Figs. 17 and 18). The clip has two prongs 126 which fit downwardly over the groove 123 of the shaft. At the opposite end each of rods 120 and 121 are

recessed to receive a compression spring 127 (Fig. 19) therein which seats in sockets 128 formed in the main frame of the machine, these springs normally urging the rods toward the ends having the clips so that when in place, the clips lock the rods securely in the frame but allow release thereof upon manual moving of the rods against the springs. A retaining wire 129 is threaded through adjacent legs of the clips on the two rods 120, 121 to secure them in assembled position. Upon release of wire 129 and withdrawal of the retainer clips, each shaft may then be withdrawn axially through the opening in the main frame 10.

It will be noted that the two rods are offset from each other in substantially the angular relationship of the carriage itself, the carriage extending to both sides of the rods so that its vertical projection includes the rods. It is thus evident that as different sizes and weights of work material are placed in the carriage, the bearings are subjected to loads and stresses which vary widely in amount, and, depending upon the way in which pressure is applied to the carriage by the operator, may vary in the direction of their application. It is important therefore that the carriage be so mounted that it is supported for free and easy reciprocating movement, and at the same time in such manner that there will not be any objectionable looseness or tendency for the carriage to bind on its supports.

The lower shaft 120 carries a bearing member 130 (Figs. 6 and 15) which has an upwardly opening socket portion 131. The upper rod 121 likewise carries a bearing member 132 of greater axial extent than member 130, and which also is provided with a downwardly opening socket member 133 which is in direct alignment with socket 131. A pin 135 is held in socket 133 by means of set screw 136 and has free sliding engagement with the cooperating socket 131. This provides for fixedly relating the two socket members, but permits limited movement of one relative to the other as necessary to compensate for any misalignment in the two shafts 120 and 121. Resilient bumpers 138 (Fig. 15) are carried at either end of bearing 132 to cushion the jar of operation at either limit of travel.

In order to provide for lubrication of the two bearings, the upper bearing member 132 is formed with a well 140 (Figs. 11 and 12) which is adapted to receive a quantity of lubricant. An opening 141 is provided in the front wall of the well, this opening being accessible from the front side of the machine and providing for application of an oil can thereto to refill the well. A wick 144 has one end extending into the well 140 and the other end preferably extending downwardly through a passage 145 formed at the side of the bearing member 132 to a position where it loops upwardly around lower guide rod 120 continuing around upper guide rod 121 with the end of the wick inserted between upper and lower assembly of the wicking, thus providing for complete lubrication of both guide rods.

The upper bearing member 132 is provided with a forwardly projecting part 150 which extends outwardly beneath the forward face 23 of the main frame member. Preferably a cover plate 151 is bolted in position, on the front face of the frame by means of bolts 152 (Fig. 4), enclosing the front side of the machine, while leaving a space 153 in the form of a slot through

which the part 150 projects and which it transverses in its reciprocating movement. A curved supporting arm 155 (Fig. 6) is detachably mounted upon the member 150, having a downwardly opening notch 156 adapted to be received over and rearwardly of a headed stud 157 secured to member 150. Likewise the arm 155 carries a clamping plate 158 and a thumb screw 159 which provides for drawing the clamping plate into engagement with the upwardly extending plate 160 formed as a part of member 150. A spring 161 normally retains the clamping plate in clearance position, thus facilitating the movement of the arm into the operative relation shown in Fig. 6. This is established by engagement of the slotted end 156 over the stud 157, and when so engaged the thumb screw 159 is tightened to securely draw the clamping plate 158 against the plate 160. A handle 162 (Figs. 2 and 4) is provided on a rearwardly extending arm 163 formed integrally with the support 155 for reciprocating the carriage.

The work carriage comprises two plates, a near plate 165 toward the operator's end of the machine, and a far plate 166 away from the operator's position, and in the forward direction of travel of the carriage during the cutting stroke, these two plates being arranged and mounted at right angles to each other (Fig. 13). Preferably the far plate 166 is mounted at a greater angle to the horizontal than plate 165, affording an improved support of the work during the cutting, and giving a longer slice, and as shown in Fig. 13 these angles may be 50° and 40° respectively. Transversely of the machine, both plates are so supported on arm 155 that they are inclined downwardly at an angle of about 45° and normal to the knife and gage plate as indicated in Figs. 2 and 6.

The near plate 165 is formed with an extended tongue portion 168 adjacent its lower side, to make sure that the material does not work beyond the rear edge of the carriage.

The far plate 166 is provided with an outer lug 170 (Fig. 8) and an inner lug 171 between which there extends the slide rod 172. This rod serves as a support for the pusher plate assembly, comprising a pusher plate arm 174 having roller bearings 175 spaced from each other and providing for both axial movement of the pusher plate arm along rod 172 and for the arcuate swinging of the pusher plate arm about the rod to lift the pusher plate away from the carriage.

In order to prevent interference between the pusher plate and the knife guard, means are provided for preventing the lifting of the pusher plate above the carriage while it is in its advance position, as shown in full lines in Fig. 8. This means comprises an inclined cam 176 (Fig. 9) located on lug 171, and which is adapted to cooperate with a cam surface 177 formed on arm 174. The relationship of these cam surfaces is such that when the arm 174 is moved inwardly to its inner limit of travel adjacent the knife, the two cam surfaces will engage to prevent the pusher plate from being lifted above the tray to any material extent, thus assuring against interference between the pusher plate and any portion of the knife or knife guard. If such operation is attempted, the cooperating sloping faces of the two cam surfaces will result in forcing the pusher plate arm rearwardly away from the knife, to such position that if lifted up no obstruction will occur.

In order to prevent the pusher plate from being

lifted entirely clear of the tray in the greater portion of its movement toward and away from the knife, the upper edge 180 of the plate 166 extends adjacent a flange 181 (Figs. 13 and 14) formed on the lower side of the pusher plate arm 174. While this permits the pusher plate arm to be swung above the carriage a limited distance, it prevents it from being lifted beyond the vertical position, and as shown in Fig. 14 it will not retain itself in this raised position but will return by gravity to its position within the carriage.

The upper edge 180 of plate 166 is relieved toward its outer edge as shown at 184 (Fig. 8), providing clearance for receiving flange 181 when the pusher plate arm is withdrawn to the outer limit of its travel away from the knife, thereby allowing the arm and pusher plate to be completely withdrawn from the tray and swung to an inoperative position.

The pusher plate 166 is provided with suitable work engaging spikes or teeth 187 on its lower surface, and its top surface 188 is formed with a continuous, long radius curvature such as that shown in Fig. 13. The pusher plate is mounted upon a shaft 190, the shaft being rotatably carried in pusher plate arm 174 as shown in Fig. 8. A handle 191 is keyed to the shaft by key 192 and a locking means 193 provides for retaining the handle in operative position thereon. The shaft extends into a boss 194 formed on the pusher plate 166 and is non-rotatably pinned therein. On the outer surface of the boss a coil spring 196 is secured by means of bolt 197, the opposite end of the spring being secured in a suitable recess 198 in arm 174. Spring 196 thus tends to turn the pusher plate relative to its supporting arm. A stop pin 199 is suitably secured in the pusher plate and extends into position where it engages a rib 200 on the pusher plate arm thus forming a stop to prevent rotation of the pusher plate relative to its arm beyond a predetermined point.

In operation, the spring 196 is pre-loaded in assembly to provide for normally rotating the pusher plate on shaft 190 relative to the arm 174. This rotation continues until limited by the engagement of stop pin 199 with rib 200, this being the position of the pusher plate which will bring it into parallelism with the face 165 of the carriage when lowered to its operative position as shown in Fig. 13. This is the position occupied by the pusher plate when it is used primarily for pushing or advancing the work material toward the knife. When however it is desired to engage the teeth 187 with the upper surface of a piece of meat or the like, which upper surface is usually not parallel with the supporting plate 165, the handle 191 is grasped and the pusher plate is twisted against the action of spring 196 to bring the teeth 187 into full gripping engagement with the upper surface of the work material. Upon release of the hand grip the spring 196 constantly tends to return the handle to the position described above in which it will be maintained in parallelism with the plate 165.

In order to receive and secure the pusher plate in its inoperative position, a locking pin 210 (Fig. 6) is mounted on the arm 155 in a position beneath the tray. The forward face of the pusher plate is provided with a guiding groove 212 (Figs. 13 and 14) which leads in at an angle to a deeper recess 213 which however does not extend entirely through the thickness of the pusher plate (Fig. 13), the groove 212 and recess 213 being separated by a land 214 which is flush with the

remainder of the face of the pusher plate. When the pusher plate is withdrawn outwardly away from the knife to the clearance position described above and held in such withdrawn position against the action of gravity, it may then be swung about shaft 172 to the inoperative position shown in dotted lines in Fig. 13. When this operation is performed by the operator without turning the pusher plate shaft relative to the pusher plate arm, that is, by allowing the handle 191 to twist freely in his hand as the assembly is being swung to its inoperative position, the action of the spring 196 assures that the guide slot 212 will be in proper position to receive the pin 210. When the pusher plate is swung around to its inoperative position, it may then be allowed to drop downward slightly on shaft 172 toward the knife, whereupon the guide groove 212 receives the pin 210, the latter in the final position of the pusher plate seating within recess 213 and against the land 214 to retain the pusher plate in inoperative position. The spring 196 facilitates the securing of the pusher plate in such inoperative position and avoids the necessity of having to seek for the groove in the partially concealed area beneath the carriage, and makes it possible to latch the pusher plate in inoperative position by a simple swinging movement followed by the final dropping of the assembly into latched position under the action of gravity. As shown in Fig. 13 the pusher plate is not entirely concealed beneath the tray but has been moved to a position where it does not interfere with the direct feeding of work material through the tray and does not extend laterally beyond the end of the carriage remote from the operator so that no additional space is required to accommodate the full stroke of the carriage.

Grinding mechanism is preferably provided in the form of a detachable grinder unit 220 (Fig. 4) which comprises the usual grinding and burring wheels carried on a suitable bracket. This unit is preferably adapted to be received in operative position upon a pin 221 (Fig. 1) on the rear face of the gage plate, being moved into grinding and burring relation with the knife blade by movement of the gage plate. In order to receive the unit in inoperative position, a similar stud 222 is carried on the lower portion of plate 151 as shown in Fig. 4, with the grinding unit being received inwardly of the plate and thus in a fully protected position.

From the above it will be clear that the present invention provides a simple and highly satisfactory construction of slicing machine of the gravity feed type.

It will be evident that the machine is constructed to make it easy to maintain the same in a clean sanitary condition, the main base member providing an impervious cover which completely overlies the mechanism and thus prevents passage of scraps or other particles downwardly to the space beneath the machine. Likewise a passage of substantial dimensions is provided rearwardly of the knife, extending between the knife support and the base itself, into which the scraps dropping from the knife may fall and from which they may be easily removed when the machine is cleaned. It will be noted that this passage is of substantial dimensions and is relatively free and clear of obstructions so that this cleaning action by the operator is greatly facilitated.

It is further found important in such gravity feed machines to assure that the carriage will

be firmly supported, and relatively free of play toward and away from the knife. It will be evident from analysis of the structure that the forces present vary substantially in both direction and amount, depending upon the size and physical location of the work material in the carriage and the pressure applied by the operator, and in accordance with the present invention a construction is provided in which the carriage is firmly supported so that even a reversal of direction of application of the forces with respect to the twisting moments applicable to the guide rods does not result in excess friction or a tendency toward binding, and does not develop play.

It is further desirable with such gravity feed construction to provide a predetermined position which will be normally assumed by the pusher plate, that position being the one in which it is parallel with the work receiving carriage. Thus when the pusher plate is picked up by the operator it is always normally in a proper position. By the application of manual pressure the operator can easily turn the pusher plate to bring it into full engagement with the upper surface of the work, but upon release it assumes its normal position and thus facilitates the handling of the material. Further this normal position is such that when the pusher plate is swung out of the carriage with the handle being allowed to turn in the hand of the operator so that the pusher plate retains its normal position relative to the arm, it will assume a relationship which is proper to establish latching engagement of the pusher plate with the retaining abutment. This is particularly advantageous in the gravity feed machine inasmuch as the latching is desirably effected under the action of gravity and it is desirable to establish and retain the parts in proper relative position where the latching engagement will be facilitated.

The entire machine is constructed simply and in such manner as to contribute to the maintenance of all parts in a proper working relation and substantially eliminating looseness or play and assure the maintenance of smooth working conditions and proper adjustment throughout.

Reference is made to our applications Serial Nos. 46,614 and 46,615, filed August 28, 1948, as divisions of this application and assigned to the same assignee as this application.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a slicing machine of the gravity feed type, a hollow base, a rotary knife, a work supporting carriage, a pair of rods for supporting said carriage for reciprocating movement relative to said knife, said base having a pair of apertures in one wall thereof for receiving said rods therethrough, said base having a pair of internal sockets in the opposite wall thereof for receiving one end of each of said rods, each of said rods having a circumferential groove therein adjacent the other end thereof, a pair of clips receivable in said grooves, spring means for urging said rods in a direction to cause said clips to be gripped between the walls of said grooves and

said apertured wall of said base when said ends of said rods are received in said sockets to secure said rods in position in said base, and means releasably securing said clips together to prevent accidental dislodgement thereof from said grooves.

2. A food slicing machine of the gravity feed type comprising a horizontal main base, a carriage having a work supporting surface, means at one side of said base supporting said carriage with said surface inclined downwardly for gravity feeding of work material thereon and with the lower portion of said surface overhanging said base, a rotary knife, mounting means for said knife on said base, said mounting means being spaced from said carriage supporting means by a substantial distance to support said knife from the rear thereof with said knife in inclined position substantially perpendicular to said carriage surface and with a major lower portion of said knife extending laterally beyond said mounting means and overhanging said base below said carriage surface, a guard for the edge of said knife secured at the rear thereof to said mounting means and projecting therefrom toward and in encompassing relation with the periphery of said knife in overhanging relation with said base portion below said knife, said portion of said base between said mounting means and said supporting means being curved downwardly below said knife and knife guard to form a trough extending lengthwise of said base and having both ends thereof open for ready access thereto from either side of said knife, said trough having the curved bottom thereof spaced below the lowest portion of said knife and knife guard by a substantial distance proportioned to provide a through passage beneath said knife and knife guard of adequate effective area for receiving the hand of the operator to clean the same.

3. A food slicing machine of the gravity feed type comprising a horizontal main base, a carriage having a work supporting surface, means on said base supporting said carriage for reciprocating movement with said surface inclined downwardly for gravity feeding of work material thereon, a cover on said base for said carriage supporting means, a rotary knife, means on said base mounting said knife from the rear thereof with said knife in inclined position substantially perpendicular to said carriage surface and in overhanging relation with said base, a guard for the peripheral edge of said knife secured at the rear thereof to said mounting means and projecting therefrom toward and in encompassing relation with the periphery of said knife in overhanging relation with said base, said base including a portion forming a trough extending lengthwise thereof between said cover and said mounting means, said trough having both ends thereof open for ready access thereto from either side of said knife, said trough having the bottom thereof curved downwardly about a substantial radius from a position adjacent said cover and beyond the lowermost portion of said knife and guard to a position adjacent said knife mounting means and above said lowermost guard portion to pro-

vide a through passage of correspondingly substantial effective area below and rearwardly of the periphery of said knife and guard for receiving the hand of the operator in cleaning said machine.

4. A food slicing machine of the gravity feed type comprising a horizontal main base, a carriage having a work receiving surface, means supporting said carriage for reciprocating movement on said base with said surface inclined downwardly at a substantial angle to the horizontal for gravity feeding of work material thereon, a cover on said base for said carriage supporting means, a rotary knife, means on said base mounting said knife from the rear thereof with the plane of said knife substantially perpendicular to said carriage surface, a guard for the edge of said knife secured at the rear thereof to said mounting means and projecting therefrom towards and in encompassing relation with the periphery of said knife in overhanging relation with said base, said base including a portion forming a trough extending lengthwise of said base between said mounting means and said cover in a direction generally transverse of the rotary axis of said knife to receive scraps from said knife and knife guard, said trough extending crosswise of said base from a position approximately below the center of said knife to a position beyond the lowermost portion of said knife and knife guard to underlie a major portion of said knife and knife guard, the portion of said trough beneath said knife guard being curved downwardly about a substantial radius to a level spaced below the lowermost portion of said guard by a distance not substantially less than one-half the width of said trough to provide adequate space in said trough for receiving the hand of the operator below said knife guard for cleaning said trough.
